UNITED STATES PATENT OFFICE.

MATHEW M. KERR, OF DETROIT, MICHIGAN, ASSIGNOR TO THE AMERICAN SPECIALTY COMPANY, OF SAME PLACE.

DESIGN FOR A NERVE-BROACH.

SPECIFICATION forming part of Design No. 32,945, dated July 17, 1900.

Application filed June 7, 1900. Serial No. 19,471. Term of patent 14 years.

To all whom it may concern:

Be it known that I, MATHEW M. KERR, a citizen of the Dominion of Canada, residing at Detroit, in the county of Wayne, State of Michigan, have invented and produced a new and original Design for a Nerve-Broach; and I do declare the following to be a full, clear, and exact description of the invention, such as will enable others skilled in the art to which it appertains to make and use the same, reference being had to the accompanying drawings, and to the letters of reference marked thereon, which form a part of this specification.

5 This invention relates to a design for a nerve-broach; and it consists in the configuration illustrated in the accompanying drawings, in which—

Figure 1 is an elevation of the broach. Fig. 2 is a transverse section on line 2 2 of Fig. 1. Fig. 3 is a transverse section on line 3 3 of Fig. 1. Fig. 4 is a transverse section on line 4 4 of Fig. 1.

The leading features in the design consist of a cylindrical shank and a triangular body 25 portion which tapers to a point, the acuminate portion of which is twisted.

A designates the cylindrical shank, B designates the triangular portion, which is substantially prismatic in shape, and C designates the twisted acuminate portion, terminating in a point D, the whole presenting an ornate and harmonious figure.

Having thus fully set forth my invention, what I claim is—

The design for a nerve-broach, substantially as herein shown and described.

In testimony whereof I sign this specification in the presence of two witnesses.

MATHEW M. KERR.
